UNITED STATES PATENT OFFICE.

ALFRED F. SANFORD, OF KNOXVILLE, TENNESSEE.

RADIO APPARATUS.

Application filed August 11, 1925. Serial No. 49,636.

This apparatus relates especially to means for bringing a radio-receiving apparatus into tune with the sending apparatus at different sending stations.

5 An object of this invention is to associate with the tuning members of a radio-receiving apparatus means for moving the tuning members into positions whereby they are brought into tune with a sending apparatus of a chosen sending station, the receiving apparatus including members bearing record receiving surfaces and movable in fixed relation with the tuning members, to the end that when the tuning members have been moved 10 into positions bringing those members into tune with the sending apparatus of a chosen sending station, suitable records may then be made on the record-receiving surfaces, which records then stand in fixed relation to the 15 then positions of the tuning members, so that thereafter those tuning members may be again brought into tune with the apparatus of that sending station by moving said tuning members until the records of said recording 20 surfaces are again in the position in which they were made. It might also be said that the members bearing the record-receiving surfaces may be moved until those records are again in the positions in which 25 they were made. For, as already stated, there is to be a fixed relation between the tuning members and the members bearing the record-receiving surfaces.

The apparatus illustrated and described by 30 this application comprises three tuning shafts and three concentric rings bearing record-receiving surfaces in approximately the same plane, said rings being rotatable on a common axis which is perpendicular to said plane. 35 One of said rings is to receive records concerning one of the tuning shafts; another of said rings is to receive records concerning another of the tuning shafts; and the third of said rings is to receive records concerning the 40 third of said shafts. These rings are movable independently of each other similar to the movements of the rings or tumblers in permutation locks. It is to be understood that the members bearing the record-receiving 45 surfaces may be brought into inter-relation otherwise than by bringing said surfaces in a common plane.

In a subordinate manner, the apparatus illustrated and described herein provides for 50 the movement of the record-receiving members at a speed different from the speed of the

corresponding tuning members. Each record-receiving member and its tuning member are connected by two to one gearing whereby the recording receiving member 60 moves twice as fast as the corresponding tuning member. Furthermore, there is associated with each tuning member means for limiting that member to a one-half rotation.

In the accompanying drawings, 65

Fig. 1 is a front elevation of a radio apparatus to which my improvement is applied;

Fig. 2 is a sectional elevation like Fig. 1, the outer wall being omitted and the three tuning shafts being cut; 70

Fig. 3 is an upright section on the line, 3—3, of Fig. 1, looking toward the right;

Fig. 4 is an upright section on the line, 4—4, of Fig. 1, looking toward the right;

Fig. 5 is a horizontal section on the line, 75 5—5, of Figs. 1, 2, 3 and 4, looking in the direction of the arrows;

Fig. 6 is an upright section on the line, 6—6, of Fig. 3, looking toward the left;

Fig. 7 is an upright section on the line 80 7—7, of Fig. 3, looking toward the right;

Fig. 8 is an upright section on the line, 8—8, of Fig. 3, looking toward the left;

Fig. 9 is an upright section on the lines, 85 9—9, of Fig. 5, looking toward the right; Fig. 10 is a perspective of a hand rest.

Referring to the drawings, A is the front wall of a casing or housing for a radio mechanism embodying my improvement. A¹ is the base of said casing. A² is the top of the casing. A³ is an outer wall rising from the base, A¹, to about half the height of the main wall, A, and spaced a short distance from the wall, A. A⁴ is an inner wall rising from the base, A¹, parallel to and spaced from the wall, A, 95 and rising a little higher than half the height of the wall, A. The upper edge of the outer wall, A³, is notched at A⁵, to receive other members as will be described further on. The middle part of the front wall, A, is correspondingly apertured at A⁶. The upper part of the wall, A, has a semi-annular aperture, A⁷. This aperture is concentric to the main shaft of the mechanism, and its concentric edges are shown slanting. 100

The purpose of this aperture is to expose the upper parts of the rotatable members bearing record-receiving surfaces.

B is the main shaft of the apparatus. The rear end of said shaft rests in a bearing, B¹, seated in the inner wall, A⁴. The outer end of said shaft is surrounded by a hub, B², 110

which rests in a bearing, B^2 , which is supported on a bracket, B^4 , which is attached immovably to the front wall, A , at the lower part of the aperture, A^6 . Said bracket extends outward through the notch, A^5 , in the outer wall, A^3 .

The front or outer end of the shaft, B , extends through the hub, B^2 , and supports a hand knob, B^5 , the knob surrounding the shaft and being immovably secured to the hub, B^2 . This shaft is to be turned by turning the knob.

At the rear of the hub, B^2 , a hub, C , loosely surrounds and is spaced from the shaft, B . At its forward end said hub has a circumferential flange, C^1 , which is surrounded and supported by a bearing, C^2 , which rests on the bracket, B^4 . A hand knob, C^3 surrounds a part of the bearing, C^2 , and extends over the forward face of the hub, C , and is secured thereto. Turning this knob will cause the turning of the hub, C , on the shaft, B , and the shaft, B , may be turned without turning the hub, C . A disc, C^4 , is concentric to the shaft, B , and attached immovably to the inner end face of the hub, C . The periphery of this disc extends into the semi-annular aperture in the wall, A . The perimeter is offset at C^5 , to bring an annular face into the plane of two other annular faces hereafter described. Said face constitutes a record receiving surface.

Adjacent the front face of the disc, C^4 , a sleeve, D , surrounds and is spaced from the hub, C , and is surrounded and supported by a bearing, D^1 , seated on the bracket, B^4 . On the outer or forward end of said sleeve is a hand knob, D^2 , partially surrounding the bearing, D^1 . On the inner end of the sleeve, D , is a disc, D^3 , which has its forward face close to the rear or inner face of the wall, A , and said disc extends outward to bring a part of its front face into the aperture, A^7 , concentric with the offset part, C^5 , of the disc, C^4 , the outer face of the disc, D^3 , and the outer face of the offset part, C^5 , being in the same plane. The part of the disc, D^3 , which is exposed in the aperture, A^7 , constitutes a record receiving surface.

A disc, B^6 , surrounds and is fixed to the shaft, B , at the rear of the disc, C^4 . The disc, B^6 , is of larger diameter than the disc, C^4 , and supports at its perimeter an annular plate, B^7 , in the plane of the disc, D^3 , and the offset part, C^5 , of the disc, C^4 . The outer face of the annular plate, B^7 , constitutes a record-receiving surface.

Thus three annular record-receiving surfaces are formed and each is adapted to be moved along the aperture, A^7 .

A tuning shaft, E , rests in a bearing, E^1 , which is seated in the inner wall, A^4 . At its rear said bearing has a flange, E^2 , resting against and secured to the rear face of the wall, A^4 . At the rear face of the flange, a

collar, E^3 , surrounds and is fixed to the shaft and serves to prevent forward movement of the shaft. On this collar are two radial pins, E^4 , placed diametrically opposite each other. On the flange, E^2 , is a horizontal stop pin, E^5 , which extends into the path of the pins, E^4 . By this means, the shaft, E , is limited to a half turn. The inner end of this shaft is connected with tuning mechanism which calls for a half turn or less to effect tuning. Such mechanism is well-known and therefore is not shown by these drawings.

The shaft, E , projects forward through the bearing, E^1 far enough to receive a spur gear wheel, E^6 , said wheel surrounding and being fixed to said shaft. Said shaft does not extend forward through the walls, A and A^3 . It terminates to leave room for the discs, B^6 and C^4 . The spur gear wheel, E^6 , meshes with an idle spur gear wheel, E^7 , which loosely surrounds a fixed shaft, E^8 , which is seated in the wall, A^4 . The wheel, E^7 , meshes with a spur gear wheel, E^9 , which surrounds and is fixed on the shaft, B , at the inner face of the inner wall, A^4 . These gear wheels are preferably so proportioned as to cause one full rotation of the shaft, B , to give to the tuning shaft, E , a one-half turn. The gear wheel, E^9 , rests against the bearing, B^1 , and prevents rearward movement of the shaft. A collar, B^8 , surrounds and is fixed to the shaft B , close to the inner face of the bearing, B^1 , and serves to hold the shaft, B , against forward movement. A circumferential flange, B^9 , on the hub, B^2 , positioned to bear against the outer face of the bearing, B^3 , also aids in holding the shaft, B , against inward movement.

At the right of the shaft, B , and at a lower level, a second tuning shaft, F , is seated in bearings, F^1 , in the walls, A , and projects loosely through the front wall, A^3 and A^4 . (Figs. 3 and 5.) On the outer or forward end of said shaft is a hand knob, F^2 , by means of which said shaft is to be turned. Between the walls, A^2 and A , a spur gear wheel, F^3 , surrounds and is fixed to the shaft, F . That wheel meshes with an idle spur gear wheel, F^4 , which loosely surrounds a shaft, F^5 , which is fixed in the front wall, A . That idle wheel meshes with a spur gear wheel F^6 , which is in the form of an annulus surrounding the hub, C , and secured by screws to the flange, C^1 , of said hub. Through said gears, the second tuning shaft, F , and the hub, C , and the disc, C^4 , must turn simultaneously; but said gears are so proportioned as to require the hub, C , to turn twice as fast as the shaft, F , turns. In other words, the disc, C^5 , is to make a full rotation while the shaft, F , makes only a one-half turn.

At the rear of the wall, A^4 , the shaft, F , is surrounded by a fixed collar, F^7 , on which are two diametrically opposite radial pins, F^8 .

On the adjacent bearing, F^1 , is a horizontal pin, F^9 , which stands in the path of the pins, F^8 . By this means the shaft, F , is limited to a one-half turn.

5 At the left of the tuning shaft, B , and at a lower level is a third tuning shaft, G , which rests in bearings, G^1 , in the walls, A and A^4 , and projects loosely through the outer wall, A^3 . At the front of the wall, A^3 , a hand knob, G^2 , surrounds and is fixed to said shaft. Between the walls, A^3 and A , a spur gear wheel, G^3 , surrounds and is fixed to said shaft. Said wheel meshes with an idle spur gear wheel, G^4 , which turns loosely on a shaft, G^5 , fixed 10 on the wall, A . This idle wheel meshes with a ring-form spur gear wheel, G^6 , which loosely surrounds the hub, C , and is immovably secured to the sleeve, D , by means of screws or otherwise. Through these gears, the shaft, G , and the sleeve, D , and the disc, D^2 , must move simultaneously. But the gears are so proportioned as to compel a full rotation of the sleeve, D , and the disc, D^2 , while the tuning shaft, G , undergoes only a one-half rotation. 15 At the rear of the rear bearing, G^1 , the shaft, G , is surrounded by a fixed collar, G^7 . On this collar are two diametrically opposite radial pins, G^8 . On the bearing, G^1 , is a horizontal pin, G^9 , in the path of the pins, G^8 . 20 These pins serve to limit the shaft, G , to only a one-half rotation.

A guide bar, H , extends across the right hand part of the aperture, A^7 , of the wall, A , the ends of said bar being secured to the wall, A , by means of screws, H^1 . To bring the body of said bar close to the record-receiving surfaces, the ends of the bar are bent to rest on the slanting faces of the wall, A . This bar is preferably slotted, as shown by the drawings, in order that the record-receiving surfaces will present a definite limited area on which writing is to be placed. Below the guide bar, H , is a hand rest, H^2 . One end of said hand rest is secured on the wall, A , by screws. The other end of said hand rest is secured on the outer wall A^3 .

On any part of the annular plate, B^7 , preferably along one of its edges, are placed a series of permanent numbers extending entirely around the plate, the series extending from one upward, the number of intervals depending upon the spacing. In Fig. 1, the numbers from 26 to 51, inclusive, (excepting 27, 28 and 30) are exposed to view. The spaces between these numbers are divided by graduation marks.

The operation of this apparatus is as follows:

To bring the apparatus into tune with a chosen sending station, any one of the three tuning shafts is brought into tune with that station by turning that shaft into the required position.

If the first tuning shaft, E , is chosen for the beginning of this operation, the hand

knob, B^5 , is turned until it has been found that the mechanism connected with the shaft, E , is in tune, motion being, as above described, transmitted from the shaft, B , to the shaft, E , by means of the three gear wheels connecting said shafts. This turning of the shaft, B , causes the turning of the disc, B^6 , and the annular record-receiving plate, B^7 , in unison with the shaft, B . When these movements cease, a certain part of the outer face of the annular plate, B^7 , (usually one of the serial numbers) is behind the slot in the guide bar, H . If the mechanism connected with the second tuning shaft, F , is next to be brought into tune with the chosen sending station, the hand knob, F^2 , of that shaft (or the knob, C^2) is turned until the desired tuning has been found. Turning that knob, F^2 , causes the corresponding turning of the shaft, F , and that causes the turning of the three gear wheels which connect the shaft, F , with the hub, C , whereby that hub and the disc, C^4 , are turned. But the hub and the disc, C^4 , turn twice as fast as the rate at which the shaft, F , is turned. When these movements cease, a part of the recording surface of the offset, C^5 , of the disc, C^4 , will be exposed through the slot in the guide bar, H .

Next the hand knob, G^2 , of the third tuning shaft, G , (or the knob, D^2) is turned to bring the mechanism connected with that shaft into tune with the chosen sending station. This movement of the shaft, G , causes the turning of the gear wheels connecting that shaft with the sleeve, D , and the disc, D^2 , said sleeve and said disc turning twice as fast as the tuning shaft, G . When these movements cease, a part of the record receiving surface presented by the disc, D^2 , is exposed in the slot of the guide bar, H .

Now a record of the positions of the three tuning shafts is to be made on the record receiving surfaces. The position of the first tuning shaft, E , is to be noted on the part of the front or outer face of the annular plate, E^7 , which is exposed in the slot of the guide bar, H . This record may consist of the initials or name, or both, of the sending station with which the apparatus has been brought into tune. The wave length of that station may also be placed on this surface. On the exposed parts of the offset part, C^5 , of the disc, C^4 , and the disc, D^2 , is placed the annular plate serial number then exposed through the slot of the bar, H . In Figs. 1 and 2, of the drawings, this number is 30. If a space between two of the serial numbers were exposed, for example, the space between 30 and 31, then 30 may be written on the members C^5 and D^2 .

When this apparatus is to be put into tune with another sending station, the three tuning shafts are turned as already described, until they are in tune with that sending station. Then, in the manner already described,

appropriate records are placed on the parts of the record receiving surfaces which are exposed through the guide bar slot. Thus records for any number of sending stations may be placed on the record-receiving surfaces.

When it is desired to again place the apparatus into tune with a sending station with which the apparatus was previously in tune, the annular plate, B⁷, is turned until the record for that station is in the guide bar slot. Then the other record members are rotated to bring into the guide bar slot the number in that slot on the plate, B⁷. It may be said that for thus resetting the apparatus, the guide bar, H, serves as an indicator.

It is to be noted that the tuning shafts, F and G, may be turned for tuning by turning the disc knobs on those shafts or by turning the corresponding knobs surrounding the shaft, B, (the knobs, C³ and D²). Because the record receiving members rotate at a higher velocity than the rate of rotation of those tuning shafts, greater accuracy can be attained by turning the record receiving members and transmitting motion from the associated gear wheels, F⁶ and G⁶, to the corresponding tuning shafts. This advantage is increased because the wheels, F⁶ and G⁶, are of less diameter than the corresponding wheels, F³ and G³. Thus a slight movement of any part of a record-receiving surface will involve a much smaller fractional rotation of the corresponding tuning shaft. In making this adjustment, the operator may be guided wholly by the movements of the record-receiving surfaces. Direct movement of the tuning shafts, F and G, may be desirable when it is sought to quickly bring those shafts through a considerable movement to approximately correct position, precise position being then attained by using the knobs, C³ and D². No provision is made for directly engaging the tuning shaft, E, for the more rapid turning of that shaft.

I claim as my invention,

1. In an apparatus of the kind described, the combination with a plurality of tuning shafts on parallel axial lines, of a plurality of parallel members shiftable independently of each other and having record-receiving surfaces near each other parts of which may be brought substantially into alignment with each other by the shifting of said members, and motion transmitting means connecting each of said shafts with one of said shiftable members, substantially as described.

2. In an apparatus of the kind described, the combination with a plurality of tuning shafts on parallel axial lines, of a plurality of parallel members rotatable independently of each other and having record-receiving surfaces near each other parts of which may be brought substantially into alignment with each other by the rotation of said members,

and motion transmitting means connecting each of said shafts with one of said rotatable members, substantially as described.

3. In an apparatus of the kind described, the combination with a plurality of tuning shafts on parallel axial lines, of a plurality of members rotatable independently of each other on a common axis and having record-receiving surfaces near each other parts of which may be brought substantially into alignment with each other by the shifting of said members, and motion transmitting means connecting each of said shafts with one of said rotatable members, substantially as described.

4. In an apparatus of the kind described, the combination with a plurality of tuning shafts on parallel axial lines, of a plurality of concentric members rotatable independently of each other and having record-receiving surfaces near each other parts of which may be brought substantially into alignment with each other by the rotation of said members, and motion transmitting means connecting each of said shafts with one of said rotatable members, substantially as described.

5. In an apparatus of the kind described, the combination with a plurality of tuning shafts on diverse axes, of a plurality of members rotatable independently of each other and having record-receiving surfaces near each other, a hand rest adjacent said record-receiving surface and motion transmitting means connecting each of said shafts with one of said rotatable members, substantially as described.

6. In an apparatus of the kind described, the combination with a plurality of tuning shafts on diverse axes, of a plurality of members shiftable independently of each other and having record-receiving surfaces near each other parts of which may be brought substantially into alignment with each other by the shifting of said members, and motion transmitting means connecting each of said shafts with one of said shiftable members, the shiftable members being given greater velocity than said shafts, substantially as described.

7. In an apparatus of the kind described, the combination with a plurality of tuning shafts on diverse axes, of a plurality of members rotatable independently of each other and having record-receiving surfaces near each other parts of which may be brought substantially into alignment with each other by the rotation of said members, and motion transmitting means connecting each of said shafts with one of said record-receiving members for diverse velocity, substantially as described.

8. In an apparatus of the kind described, the combination with a plurality of tuning shafts on diverse axes, of a plurality of members rotatable independently of each other

- on a common axis and having record-receiving surfaces near each other parts of which may be brought substantially into alignment with each other by the rotation of said members, and motion transmitting gearing connecting each of said shafts with one of said record-receiving members the latter receiving the higher velocity, substantially as described.
9. In an apparatus of the kind described, the combination of an upright wall having a semi-annular opening, the base of which is horizontal, a main shaft perpendicular to and supported on said wall on the axis of said opening, a record-receiving member supported by and rotatable with said shaft at the rear of said wall and extending into said opening, a tuning shaft, gearing connecting said tuning shaft and said main shaft, a hub loosely surrounding the main shaft, a record-receiving member mounted on said hub at the rear of said wall and extending into said opening, a second tuning shaft, and gearing connecting said shaft and said hub, substantially as described.
10. In an apparatus of the kind described, the combination of an upright wall having a semi-annular opening, the base of which is horizontal, a main shaft perpendicular to and supported on said wall on the axis of said opening, a record-receiving member supported by and rotatable with said shaft at the rear of said wall and extending into said opening, a tuning shaft, gearing connecting said tuning shaft and said main shaft, a hub loosely surrounding the main shaft, a record-receiving member mounted on said hub at the rear of said wall and extending into said opening, a second tuning shaft, and gearing connecting said shaft and said hub, substantially as described.
11. In an apparatus of the kind described, the combination of an upright wall having a semi-annular opening, a bearing bracket on the axial line of said opening, a driving shaft on said bracket, a hand knob on the outer end of said shaft, a tuning shaft at the rear of said wall, and gearing between said tuning shaft and the rear end of said driving shaft, substantially as described.
12. In an apparatus of the kind described, two concentric rotary driving members, a record-receiving member supported by each of said driving members, a tuning shaft, gear- ing connecting said shaft with one of said driving members, a second tuning shaft outside the axial line of the first tuning shaft, and gearing connecting said tuning shaft with the other rotary driving member, substantially as described.
13. In an apparatus of the kind described, the combination of a rotary driving member having a hand knob, a tuning shaft having a hand knob, a record-receiving member supported by and rotatable with the driving member, and gearing connecting the driving member and the tuning member, substantially as described.
14. In an apparatus of the kind described, the combination with a plurality of tuning members on parallel axial lines, of a plurality of concentric record members, and means placing each of said tuning members into operative relation with a corresponding record member for simultaneous turning of said member and the tuning member, substantially as described.
15. In a radio receiving mechanism the combination with two parallel independently movable tuning members, of two independently movable record-receiving members adjacent each other, means placing one of said tuning members into operative relation with one of said record-receiving members for movement, and means in operative relation with the other record-receiving member for moving the latter, whereby each tuning member may be moved into tune position and the companion record-receiving member moved into a new position and adjacent records then made on said two surfaces relative to each other and to a stationary part of the mechanism, substantially as described.
16. In an apparatus of the kind described, the combination of an upright wall, a bracket seated on the outer side of said wall and comprising a plurality of bearings on a common axial line, a plurality of tuning shafts, a plurality of rotatable members free from each other and supported on said bearings, record-receiving members supported on said rotatable members, and gearing intermediate said rotatable members and said tuning shafts.

In testimony whereof I have signed my name, this 24th day of July, in the year one thousand nine hundred and twenty-five.

ALFRED F. SANFORD.
